Primary Examiner—Prabhakar G. Deshmukh*Assistant Examiner*—Richelle Shelton*Attorney, Agent, or Firm*—Foley & Lardner**[57] CLAIM**

The ornamental design for a receiver combined with a video tape recorder, as shown and described.

DESCRIPTION

FIG. 1 is a perspective view of a first embodiment of a receiver combined with a video tape recorder showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof;

FIG. 8 is a perspective view of a second embodiment of a receiver combined with a video tape recorder showing my new design;

FIG. 9 is a top plan view of the embodiment of FIG. 8;

FIG. 10 is a left side elevational view of the embodiment of FIG. 8;

FIG. 11 is a front elevational view of the embodiment of FIG. 8;

FIG. 12 is a right side elevational view of the embodiment of FIG. 8;

FIG. 13 is a rear elevational view of the embodiment of FIG. 8 and,

FIG. 14 is a bottom plan view of the embodiment of FIG. 8.
